UNITED STATES PATENT OFFICE.

JAMES HOMER PLACE, OF WARREN, PENNSYLVANIA.

VAPORIZER FOR INTERNAL-COMBUSTION ENGINES.

Application filed October 15, 1921. Serial No. 507,992.

To all whom it may concern:

Be it known that I, JAMES H. PLACE, a citizen of the United States, residing at Warren, in the county of Warren and State 5 of Pennsylvania, have invented certain new and useful Improvements in Vaporizers for Internal-Combustion Engines; and I do hereby declare the following to be a full, clear, and exact description of the invention, such as will enable others skilled in the art to which it appertains to make and use 10 the same.

My invention relates to new and useful improvements in vaporizers for internal 15 combustion engines, and has for its object to provide a vaporizer which is automatically controlled, compact and simple in construction, requires no special fittings and can be used on the engines of any automobile.

Another object of my invention is to provide a vaporizer adapted to be secured to the side of the exhaust manifold of a gasoline engine, thereby being automatically 20 heated.

A further object of my invention is to furnish a vaporizer which is adapted to receive a constant supply of water from the water jacket of the motor, thus insuring 25 steam, which is far more practical than using cold water or moist air from tanks, reservoirs, or from the radiator of the car.

By the use of this device, the formation 30 of carbon is minimized and a smoothly running engine is assured.

A still further and desirous improvement 35 of my vaporizer, is that it greatly decreases the vibration of the motor, due to the constant and steady amount of fully vaporized fuel admitted to the combustion chamber of each cylinder, thus causing a smooth running motor.

All of the above objects and improvements have been proved to be accurate facts 40 by many successful tests.

With the above and other objects in view, which will appear as the description proceeds, the invention consists in the novel features herein set forth, illustrated in the 45 accompanying drawings, and more particularly pointed out in the appended claims.

Referring to the drawings, numerals of like character designate similar parts throughout the several views, in which—

50 Fig. 1 is a view of my improved vaporizer in place on an automobile engine.

Fig. 2 is a cross section in detail of the vaporizer, and

Fig. 3 is a view taken on line 3—3 of Fig. 2.

In the drawing 1 designates any automobile engine, 2 is the exhaust manifold of said engine, to which is secured the main body or vaporizing chamber 3, of my improved vaporizer. The vaporizing chamber 65 is secured in place by means of a stud 11, which is threaded and screwed in the recess 20 of the chamber and then in the exhaust manifold 2.

4 represents the water inlet fitting, which 70 is provided with a screw adjustment 5, which allows approximately fifteen drops of water per minute to spray against the hot walls 10 of the vaporizing chamber 3. This chamber receives its heat from the exhaust manifold.

By means of the tube 6, the chamber is connected to the water jacket 7 of the motor, thus receiving a supply of pre-heated 75 water or vapor.

8 represents the air inlet, provided with a ball and spring check 9, which automatically regulates the supply of air.

The vapor is delivered from the chamber 3 to the inlet manifold 15 by means of a 85 tube 14 and a cock of any desired type 13, which is secured to the chamber at 12.

To overcome the accumulation of water in the vaporizing chamber when the car is not in motion, I provide the device with 90 an outlet 17 including a spring and ball check 18, the ball being drawn up against the spring by the suction, when the motor is started, enough to allow the accumulated water to escape.

The operation of my device is obvious. A constant flow of heated water or vapor comes from the water jacket of the motor, and is sprayed against the inner walls of the vaporizing chamber, and mixed with the air supply, which is automatically regulated by ball and spring checks. This mixture is then admitted into the intake manifold and comes into contact with the gasoline vapor and breaks up any unvaporized 100 particles of the fuel, thus minimizing the deposit of carbon and assuring a smoothly running engine.

From the foregoing, I believe that the construction, operation and advantages of 110 my device may be clearly understood without further description, and in conclusion I

may state that the constructional details may be modified considerably without departing from the spirit of the invention, as set forth in the following claims.

5 What I claim and desire to secure by Letters Patent is:—

1. The combination with means for furnishing a mixture of air and steam to the intake conduit of an internal combustion engine, including a substantially disc-shaped vaporizing chamber, of a stud carried by one of the flat faces of said chamber and adapted to be fitted to the exhaust manifold of the engine so that one of the flat faces of said chamber will be opposite the engine.

2. Means for furnishing a mixture of air and steam to an internal combustion engine comprising a vaporizing chamber cylindrical in cross section and provided with

two diametrically opposite ports in its circumference, one of said ports being an air inlet and the other a water outlet and both being fitted with check valves, two additional diametrically opposite ports, means to connect one of said ports to a water supply and means to connect the other of said ports to the intake manifold of said engine, valves fitted adjacent both said last named ports, said chamber being provided with a stud, by means of which it may be secured to the exhaust manifold of an engine, and thereby heating said chamber.

3. The combination as claimed in claim 1, wherein the vaporizing chamber is provided with thick walls, adapted to retain the heat from the exhaust manifold.

In testimony whereof I affix my signature.

JAMES H. PLACE.
